UNITED STATES PATENT OFFICE.

OLIVER WESTON, OF CLEVELAND, OHIO.

GAME DEVICE.

1,006,516.

Specification of Letters Patent. Patented Oct. 24, 1911.

Application filed January 14, 1911. Serial No. 602,629.

To all whom it may concern:

Be it known that I, OLIVER WESTON, a citizen of the United States, residing at Cleveland, in the county of Cuyahoga and State of Ohio, have invented certain new and useful Improvements in Game Devices, of which the following is a specification.

This invention relates to games, and especially to games of the pool variety, having for its object to provide an interesting and amusing pastime for any number of players, and to provide a pool game which can be played and enjoyed by the unskilled player as well as the skilled player. Further objects will be evident from the herein-after description.

The invention is embodied essentially in a pool table mounted in a frame and capable of manipulation by hand to "pocket" the balls thereon, thus dispensing with the cue, with which it is difficult to shoot accurately unless the player is well experienced or skilled in the use thereof.

The device is illustrated in the accompanying drawings, in which similar reference figures indicate similar parts, and in which—

Figure 1 is a perspective of the game device. Fig. 2 is a cross section through the central apertures of a modified form. Fig. 3 is a longitudinal central section of the game device as shown in Fig. 1. Fig. 4 is a plan view of a modified form.

The frame is shown at 11, and the lower portion thereof forms the receptacle 17, having a sloping bottom 18. This bottom slopes from the rear end to the front, and the same, as well as the receptacle extends forwardly beyond the frame 11 to form the extension 17' of the receptacle, which is exposed. This frame is rectangular in shape, and the front end 19 thereof is removable therefrom by means of screws 24 for the purpose hereinafter described. The said end is spaced above the bottom 18 to form a passage thereunder. Along the sides of the frame and on the inside thereof are ribs or tracks 22.

A table 12 is slidably mounted in the said frame and on the said ribs 22 by means of the channels 29 engaged thereby. This table is shorter than the frame 11 and is also rectangular in shape, the ratio of the sides of such tables being usually two to one. Therefore, the said table is slideable longitudinally in the said frame. This table 12

has an upper playing surface 13, and has disposed around the periphery thereof corner apertures or passages and centrally located apertures or passages 15, as is common in the standard pool table. Between the said apertures 15 and around the periphery of the table are cushions 16 of rubber or suitable material. Between the end 19 of the frame and the front end of the table are arranged coiled springs 23, which extend into the recesses 27 in the front end of the said table. Rods or fingers 21 are arranged within the springs 23 and have their inner ends secured to the table 12 and their outer ends slideable in the end 19 of the frame. One of the said rods or fingers 21, preferably the central one 20, has its front end projected beyond the end 19 of the frame and has an outer knob 26. Rubber headed tacks 28 are arranged on the inner face of the rear end of the frame, and lie in the path of the table 12. Loops 25 may also be provided on the front end of the table. The table can be removed by removing end 19.

The playing surface of the table 12 may be concaved as shown at 13' in the modification shown in Fig. 2. In the form shown in Fig. 4, the coiled springs 23 are substituted by an elliptical spring 23', the finger or rod 21' being secured to the front end of the table.

The balls or the like 14, with which the game is played, are arranged on the playing surface of the table, and by pulling on the knob 26 and by holding the frame stationary, the table is pulled forwardly in the said frame against the compression of the springs or spring and when released returns to its normal position at the rear end of the frame with an impact against the rubber tacks or cushions 28, which causes the balls to scatter, "kiss", bound back from the cushions 16, etc., to remain upon the table or drop down apertures 15. In passing down the apertures or passages 15 the balls drop onto the bottom 18 and due to the decline of same they are forced to roll to the extension 17'.

Numerous games can be played with this game device, which are common, for example; the balls, fifteen in number, can be arranged pyramidically on the table, and the players can take turns in trying to obtain the most number of balls by "pocketing" same into the apertures 15, or the balls can be numbered and the sum thereof obtained

by each player indicating the winner. As these and other pool games are common, a further description thereof is not thought necessary.

5. When playing with the table having a concave playing surface, the balls tend to return to the center of the table after "shooting", and gives each player more of an equal chance. The balls rolling into the extension 10 17' can easily be removed, and counting of the balls "pocketed" is facilitated. Instead of pulling the knob 26 to move the table, the said table can be drawn against the compression of the spring or springs by pulling 15 on the loops 25 with the fingers of the player.

It is also understood that various alterations and additions can be made to the invention, within the scope of the appended 20 claims, and that no limitations are inferred by the specific construction shown and described.

Having described my invention, what I claim as new is—

1. A game device comprising a frame 25 having a lower receptacle which extends out from the said frame and the bottom of the said receptacle being inclined from the said extended portion, a table slidably mounted within the said frame above the said receptacle and having an upper playing surface and apertures therein passing through the table to the said receptacle, a spring having tension between the said frame and table, cushions around the periphery of the said 30 table, and means for pulling the said table against the tension of the said spring.

2. A game device comprising a frame having a lower receptacle, a table slidably mounted within the said frame above the 40 said receptacle and having an upper playing surface and apertures therein passing through the table to the said receptacle, a spring having tension between the said frame and table, cushions around the periphery of the said 45 table, and means for sliding the said table against the tension of the said spring.

3. A game device comprising a frame, a table slidably arranged on the said frame 50 and having an upper playing surface and apertures therein, a spring having compression between the said frame and table, cushions around the periphery of the said table, and means for pulling the said table against 55 the compression of the said spring.

4. A game device comprising a frame, a table slidably arranged on the said frame

and having an upper playing surface and a plurality of apertures therein disposed around the periphery thereof, a spring having tension between the said frame and table, cushions around the periphery of the table between the said apertures, and a finger projecting from the said table and having a knob thereon to allow the table to be pulled against the tension of the said spring.

5. A game device comprising a frame having a lower receptacle which extends out from the said frame and the bottom of the said receptacle being inclined from the said extended portion, a table slidably mounted within the said frame above the said receptacle and having an upper playing surface and apertures therein passing through the table to the said receptacle, cushions around the periphery of the said table, and means for sliding the said table.

6. A game device comprising a rectangular frame having the lower end extended at one end and the bottom thereof inclined 80 from the said end, a rectangular table slidably mounted longitudinally in the said frame and spaced above the said bottom, the said table having an upper playing surface and apertures arranged at the corners and 85 sides thereof which pass through the said table, a spring arranged between one end of the said frame and table tending to hold the said table at one end of the frame, cushions around the periphery of the said table between the said apertures, and a finger projecting from the said table out through the said frame and having an outer knob to allow the table to be pulled against the tension 90 of the said spring.

7. A game device comprising a frame, a table slidably arranged on the said frame and having an upper playing surface which slopes from the sides and ends thereof to the center of the said table and the said table 100 having a plurality of apertures arranged around the periphery thereof, cushions around the periphery of the said table between the said apertures, a spring having tension between the said frame and table, 105 and means for sliding the said table on the said frame against the tension of the said spring.

In testimony whereof I do affix my signature in presence of two witnesses,

OLIVER WESTON.
